HANGING SUPPORT FOR PLANTS

Lee H. Stevens, P.O. Box 710,
Escondido, Calif. 92025

Filed Aug. 12, 1974, Ser. No. 496,632

Term of patent 14 years

Int. Cl. D11—02

U.S. Cl. D6—113

FIG. 1 is a perspective view of a hanging support for plants, showing my new design.

FIG. 2 is a rear elevational view thereof.

FIG. 3 is a side elevational view as taken from the left hand side of FIG. 2.

FIG. 4 is a bottom plan view thereof.

I claim:

The ornamental design for a hanging support for plants, substantially as shown.
